Term of patent 14 years

Int. Cl. D11—01

U.S. Cl. D45—4

FIG. 1

FIG. 2

FIG. 3

FIG. 4

FIG. 1 is a top plan view of an expansible link chain for a bracelet embodying my new design with the links in contracted position;

FIG. 2 is a view similar to FIG. 1 with the links in an expanded position, portions of the conventional appearing bottom links being visible between the expanded top links;

FIG. 3 is an enlarged top plan view of a single top link of the expansible chain; and

FIG. 4 is an enlarged perspective view of the top link shown in FIG. 3.

The characteristic feature of my design resides in the combination of the angular orientation of the ridges of the bark-like ornamentations of the panels at each side of the central elements in combination with the uniformly tapering plain surfaced end panels of the links.

I claim:

The ornamental design for an expansible link chain for a bracelet or similar article, substantially as shown and described.
